GASEOUS TUBE ACCUMULATOR

Robert B. Koehler, Hopewell Junction, and Edward J. Rabenda, Poughkeepsie, N. Y., assignors to International Business Machines Corporation, New York, N. Y., a corporation of New York

Application December 21, 1950, Serial No. 201,963

10 Claims. (Cl. 315—84.6)

This invention relates to an electronic accumulating device of the gaseous glow transfer type wherein means are provided within a single envelope for accommodating positive and negative numbers in true and complement forms, respectively.

A principal object of the invention is to provide a novel accumulating device of the gaseous glow transfer type wherein the presence of a negative balance is immediately determined and wherein positive numbers are stored in true form and negative numbers are stored in complement form.

Another object of the invention is to provide a gaseous accumulator tube of the glow transfer type wherein a first closed glow transfer path is provided to accommodate true members and a second closed glow transfer path is provided to accommodate complement numbers, means being provided to effect selected glow transfer from one path to the other.

Another object of the invention is to provide a gaseous accumulator tube of the glow transfer type wherein readout of the manifestations stored therein is accomplished by applying thereto a number of manifestations equal to the storage capacity of the accumulator to transfer the glow discharge through one cycle of operation, the direction of the glow transfer being determined by the polarity of the stored manifestations.

A further object of the invention is to provide a novel gaseous accumulating device wherein positive manifestations are stored in true form and negative manifestations are stored in complement form.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a diagrammatic showing of one order of the accumulator device of the invention, and

Fig. 2 is a rolled-out longitudinal cross-sectional view of a portion of the cathode structure of the device shown in Fig. 1.

Briefly, each order of the accumulator of the invention includes a gaseous discharge tube of the glow transfer type wherein a glow discharge is repeatedly transferred along a predetermined closed glow transfer path in response to certain preselected manifestations. Glow transfer is effected along one closed glow transfer path when reading in manifestations or reading out positive manifestations and is effected along another closed glow transfer path when reading out negative manifestations. A predetermined signal, obtained in any conventional manner, is conveyed to the tube to indicate when the manifestations to be stored are positive and when they are negative. This signal determines which of the glow transfer paths the subsequent glow transfer will follow when read out is effected. Receipt of each subsequent manifestation then causes glow transfer from one terminal of glow discharge to the next preselected adjacent one in accordance with the principles more fully set

2

forth in the application of Richard K. Steinberg, Serial No. 192,199, filed October 26, 1950, now Patent No. 2,621,313.

The tube shown has a capacity of ten positive manifestations and ten negative manifestations. To accommodate the ten positive manifestations there are provided ten digit position cathodes and ten transfer cathodes alternately interspersed to form a closed glow transfer path. Each of these cathodes is formed as an open-ended cylinder and arranged parallel to the others so that they collectively define a generally cylindrical structure wherein one end of each cathode is substantially equidistant from a common anode. Each cathode is composed of a plurality of materials of different surface characteristics and is so formed or arranged that a region of preferential glow transfer is established between each cathode and one other cathode. When a glow discharge is present between any one of the cathodes and the anode, that glow discharge will always include only a preselected area of that cathode. A transfer wire projects within the region of intense ionization created by the glow discharge and effects a transfer of the glow discharge to another preselected cathode in response to the receipt of the next predetermined electrical manifestation by the tube. The transfer wire and proper insulation (not shown herein) of the cathodes from each other insures certain transfer of the glow discharge.

To accommodate the ten negative manifestations there is also provided ten complement position cathodes and ten transfer cathodes alternately interspersed along a closed glow transfer path. The cathodes are similar to those used to accommodate the positive manifestation and each is parallel to the other and equidistant from the common anode. The complement position cathodes are arranged inwardly from the concentrically with the digit position cathodes for accommodating the positive manifestations. The transfer cathodes for accommodating the negative manifestations are arranged inwardly from and concentrically with their associated complement position cathodes. Hence, the complement position cathodes and the transfer cathodes for accommodating the negative manifestations each collectively define a generally cylindrical structure of different diameter, while both the digit position and transfer cathodes for accommodating the positive manifestation collectively define the same generally cylindrical structure.

Referring more particularly to Fig. 1 there is shown in diagrammatic form one order of an accumulator. The gaseous tube of the invention is enclosed in an envelope 10. Immediately within the envelope 10 there is shown ten digit position cathodes Cp-0 to Cp-9 inclusive, arranged to form a general cylindrical structure. There is also included in the same general cylindrical structure ten transfer cathodes C-0 to C-9 inclusive. The cathodes are so arranged that a transfer and position cathode are alternately encountered when proceeding around the general cylindrical structure.

The arrangement of the cathode is more fully understood by referring to Fig. 2 which is a rolled-out cross-section of the portion of the cylindrical structure including the cathodes C-0, C-1, Cp-0, and Cp-1. It is noted that each of the cathodes is an open-ended cylinder having one end equi-distant from a common anode A (not shown in Fig. 1). The cathodes are coated in accordance with the principles set forth in the application referred to above so that the existence of a glow discharge between the inner surface of any cathode and the anode produces a lower voltage drop than a glow discharge between the outer surface of that cathode and the anode. Accordingly, a glow discharge will exist between the anode and the inner surface of any cathode and preference to any other

place on the cathode and if a voltage drop should exist between the anode and a difference place on the cathode, it will automatically migrate along the cathode until it is confined to the inner surface thereof. A transfer wire *gt* projects from each position and transfer cathode to an adjacent cathode performing the other function, i. e., to the adjacent position or transfer cathode as the case may be. The free end of each wire is positioned between the open end of a cathode nearest the anode and the anode so that when a glow discharge exists between that cathode and the anode the transfer wire extends into a region of intense ionization created by the glow discharge and effects a transfer of the glow discharge to the cathode to which its other end is affixed in response to the receipt of a predetermined electrical manifestation by the tube. The transfer wire and the insulating strips *I* (not shown in Fig. 1) arranged between successive cathodes insure certain transfer of the glow discharge around the closed glow transfer path. Detailed structure and description of the operation is found in the application referred to above. The ionic isolating scheme set forth therein is utilized by the present invention to ionically isolate each cathode from every other.

The cathodes *Cp-0* to *Cp-9* inclusive, and *C-0* to *C-9* inclusive, are used to store manifestations whether such manifestations be in complement or true form.

Referring again to Fig. 1 there are shown two additional groups of cathodes. The cathodes in the group nearest those described above are designated *Ccp-0* to *Ccp-9* inclusive, and function as complement position cathodes. The cathodes in the group nearest the center of the envelope *10* are designated *Cc-0* to *Cc-9* inclusive, and function as glow transfer cathodes. It is seen that the complement position and glow transfer cathodes each form different generally cylindrical structures but it is understood that such is not a requirement of the invention. These two groups of cathodes *Ccp-0* to *Ccp-9* inclusive, and *Cc-0* to *Cc-9* inclusive, are used herein for the sole purpose of converting a number in complement form to a true number.

It is readily seen from Fig. 1 that numerous transfer wires *gt* are required to accomplish the purpose of the invention. Each digit position cathode *Cp-0* to *Cp-9* respectively, includes a transfer wire affixed thereto and extending into the region of intense ionization associated with the corresponding complement position cathode *Ccp-9* to *Ccp-0* respectively. Also, each complement position cathode *Ccp-9* to *Ccp-0* respectively, includes a transfer wire affixed thereto and extending into the region of intense ionization associated with the corresponding digit position cathode *Cp-0* to *Cp-9* respectively. Hence, upon receipt of proper voltage changes by the tube a glow discharge may be transferred from any digit position cathode to the corresponding complement position cathode and vice versa. It is seen that the number designation of the cathodes between which the glow transfer will take place are nine's complements of each other.

The glow transfer wires between the complement position and complement transfer cathodes are provided to effect glow transfer therebetween in accordance with the same general scheme utilized by the position cathodes *Cp-0* to *Cp-9* inclusive, and the transfer cathodes *C-0* to *C-9* inclusive. A transfer wire *gt* is affixed at one end of each complement position cathode and has its other end extending into the region of intense ionization of the complement transfer cathode designated by the same numeral. For example, the transfer wire affixed to the complement position cathode *Ccp-9* has its other end extending into the region of intense ionization associated with the complement transfer cathode *Cc-9*. Also, a transfer wire *gt* is affixed at one end of each complement transfer cathode and has its other end extending into the region of intense ionization of the complement position cathode designated by the next lower numeral. For example, the transfer wire *gt* affixed to the comple-

ment transfer cathode *Cc-9* has its other end extending into the region of intense ionization associated with the complement position cathode *Ccp-8*. However, it is obvious that the transfer wire affixed to the complement transfer cathode *Cc-0* has its other end extending into the region of intense ionization associated with the complement position cathode *Ccp-9* so that a continuous glow transfer path is provided.

As explained in the application referred to above, the free end of a transfer wire captures the glow discharge from the cathode nearest it and the glow is transferred along the wire to exist between the cathode to which that transfer wire is affixed and the anode. It is seen, therefore, that the direction of a glow transfer between the storing cathodes, *Cp-0* to *Cp-9* inclusive, and *C-0* to *C-9* inclusive, is counterclockwise. On the other hand, the arrangement of the transfer wires on the complement cathodes is such that the direction of the glow transfer is clockwise. Hence, to read out a positive number it is necessary that a glow discharge be transferred in a counterclockwise direction within the tube, and to read out a negative number it is necessary that a glow discharge be transferred in a clockwise direction within the tube.

25 The heavy lines connecting the various cathodes within the tube are voltage supply lines. The position cathodes *Cp-1* to *Cp-8* inclusive, are commonly connected to a terminal *15*. The position cathode *Cp-0* is connected to a terminal *16*, and the remaining position cathode *Cp-9* is connected to terminal *17*. The transfer cathodes *C-0* to *C-9* inclusive, are commonly connected to an input terminal *18* as are the complement transfer cathodes *Cc-0* to *Cc-9* inclusive. The complement position cathodes *Ccp-1* to *Ccp-9* inclusive, are commonly connected to a terminal *19*, and the remaining complement position cathode *Ccp-0* is connected to a terminal *20*.

30 The position cathode *Cp-9* of each order of the accumulator is individually connected to a terminal *17*. In operation, when the total stored in the accumulator is negative a glow discharge will exist between the 9 position cathode *Cp-9* of the highest order and the anode. The signal thus provided is used to energize a conventional readout minus relay, the contacts of which are shown diagrammatically at *21*. The armature *22* of the relay is connected to a terminal *23* supplied with a suitable positive voltage such as, for example, +150 volts. The armature *24* of the relay is connected to a terminal *25* to which the output of the order is supplied. The terminals *15*, *16* and *17* are connected through suitable resistors to the single relay contact *27U*. The terminals *19* and *20* are connected through suitable resistors to the single relay contact *28L*. The terminal *16* is connected directly to the relay contact *29U* and the terminal *20* is connected directly to the relay contact *30L*.

35 The electrical manifestations to be stored are applied to the input terminal *18* connected to all of the transfer cathodes of the tube.

40 It is assumed that the tube is in the zero or starting position with a glow discharge existing between the position cathode *Cp-0* and the anode (not shown). Such may be accomplished in any conventional manner such as set forth in the application referred to above.

45 To effect storage an electrical manifestation is applied to the input terminal *18* for each digit to be stored. The manifestations employed herein are shown as negative square wave pulses but it is understood that various other type input pulses may be used.

50 When the negative going front of the first square wave pulse is applied to the input terminal *18* the voltage difference between the common anode and each of the cathodes connected to the terminal *18* is increased. As a result the voltage difference between the anode and the transfer cathode *C-1* is much greater than that across the glow discharge existing between the anode and the cathode *Cp-0*. As a consequence the glow discharge is trans-

ferred from the cathode $Cp-0$ along the transfer wire gt to the cathode $C-1$ to which that transfer wire is affixed. The glow discharge continues between the cathode $C-1$ and the anode until the voltage change represented by the positive going trailing edge of the input pulse is applied to the terminal 18.

At this time, the voltage difference between the anode and each of the cathodes $Cp-0$ to $Cp-9$ becomes greater than that between the anode and the cathode $C-1$ where the glow discharge exists. As a result that glow discharge is transferred and exists between the cathode $Cp-1$ and the anode until another pulse is applied to the terminal 18.

Each subsequent input pulse causes the glow discharge to be transferred to the next position cathode having the next higher numerical designation. This counterclockwise transfer of the glow discharge continues with each pulse so that each tenth input pulse transfers the glow discharge to the position cathode $Cp-0$ to thereby complete one cycle of operation. This produces an output pulse which is transferred to the output terminal 25.

The application of input pulses to the input terminal 18 results in their storage as stated above and such storage takes place irrespective of whether or not the input pulses represent positive or negative quantities. However, in accordance with conventional accounting machine practice, if the quantity stored is negative the number of input pulses applied to the input terminal 18 is the nines complement of the actual value of the quantity. For example, a -7 would be stored in the accumulator as a 2 so that after its storage was effected a glow discharge would exist between the position cathode $Cp-2$ and the anode. Further, in accordance with conventional practice the existence of a glow discharge between the position cathode $Cp-9$ of the highest order of the accumulator and its anode denotes the existence of a negative balance in the accumulator. When such occurs a negative voltage will appear at the terminal 17 connected to the cathode $Cp-9$. This pulse may be utilized to energize a readout minus relay such as is diagrammatically represented by 21 or a suitable electronic switch may be used in place of the relay if operation faster than the relay can perform is desired.

The relay is so arranged that the armatures 22 and 24 make contact with the contacts 28L and 30L before they are disengaged from the contacts 27U and 29U respectively. As soon as the contacts 28L and 30L are connected in the circuit the complement position cathodes are connected through the contact 28L to the terminal 23 supplied with a positive voltage of +150 volts, and the cathode $Cp-0$ is connected through the contact 30L to the output terminal 25. When the contacts 27U and 29U are disengaged from their respective armatures the cathodes $Cp-1$ to $Cp-9$ are disconnected from the +150 volts supply terminal 23 and the cathode $Cp-0$ is disconnected from the output terminal 25. Hence, only readout of the negative quantity stored in the tube will be accomplished in response to pulses applied to the input terminal 18.

When the relay is energized to read out minus the glow discharge existing between any storage position cathode and the anode will be transferred from that cathode to the complement position cathode representing the nines complement of the storage position cathode to which the glow discharge existed just prior to energization of the relay. For example, if a glow discharge exists between the storage position cathode $Cp-8$ and the anode just prior to the energization of the relay to readout minus it is transferred to the cathode $Ccp-1$ upon energization of the relay. When the armature 22 engages the contact 28L the +150 volts is applied to the cathode $Ccp-1$, and when the armature disengages the contact 27U the voltage is removed from the cathode $Cp-8$ and the glow discharge moves along the transfer wire extending into the area of intense ionization associated with the cathode $Cp-8$ and affixed to the cathode $Ccp-1$ until it assumes a state of

stable discharge between the cathode $Ccp-1$ and the anode.

To fully understand the conversion of the complement entry to the true value of the entry it should be remembered that the read in and read out operations are controlled by a conventional IBM punched card wherein the card is fed lengthwise with the bottom edge of the card being read first. Actual read in or storage in the accumulator is accomplished by nine successive pulses each of which occurs a preselected time after the corresponding card pulse. A total of ten readout pulses are used during every readout cycle. The extra or tenth pulse is termed the "hot ten" and occurs at the beginning of the cycle just prior to the reading of the 9 card position. The production of these required operating pulses is well known to the art and does not constitute part of this invention. It is also clear that the application of the invention is not confined to such a system of operation but may be adapted to any system where the storage and readout of true and complement numbers is to be accomplished.

The negative front of the first readout pulse (hot ten) increases the voltage difference between the anode and each of the complement cathodes $Cc-0$ to $Cc-9$ inclusive. Since the transfer wire affixed to the cathode $Cc-2$ has its free end extending into the region of intense ionization associated with the cathode $Ccp-1$ the glow discharge is transferred along that wire and exist in stable discharge between the anode and cathode $Cc-2$ so long as the readout pulse is at its maximum negative value. When the trailing edge of the pulse if finally applied to the terminal 18 the voltage difference between the anode and each of the cathodes $Cc-0$ to $Cc-9$ inclusive, is decreased to the extent that it is less than the voltage difference between the anode and each of the cathodes $Ccp-0$ to $Ccp-9$ inclusive. As a result, the transfer wire affixed to the cathode $Ccp-2$ and having its free end extending into the region of intense ionization associated with the cathode $Cc-2$ transfers the glow discharge to the cathode $Ccp-2$ where it exists in a state of stable discharge until the next readout pulse is applied to the terminal 18. Each successive readout pulse advances the glow discharge to the next higher numbered complement position cathode. Finally, the ninth readout pulse advances the glow discharge from the cathode $Ccp-9$ to $Ccp-0$. An output pulse is then transferred from the cathode $Ccp-0$ to its terminal 20 and therefrom over the lead connected thereto, the contact 30L and armature 24 to the output terminal 25. This output pulse produced in response to the ninth readout pulse, including the "hot ten" pulse, indicates that the tens complement of the true negative value is 8. This output pulse occurs at 2 time of the card cycle thereby indicating that the true value of the negative quantity stored is 2.

The tenth or last readout pulse then transfers the glow discharge from the cathode $Ccp-0$ to the cathode $Ccp-1$ where it remains until the readout minus relay is restored to its initial condition.

When the relay is so restored the glow discharge is transferred along the transfer wire affixed to the cathode $Cp-8$ and extending into the region of intense ionization associated with the cathode $Ccp-1$ until it reaches a condition of stable glow discharge between the cathode $Cp-8$ and the anode. The readout cycle is now completed and the accumulator is reset with the original stored quantity in it.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. An accumulating gaseous discharge device of the glow transfer type including an anode; a first group of digit representing and glow transfer cathodes alternately arranged along a glow transfer path to effect glow transfer in one chosen direction along said path; an input terminal to which electrical impulses are applied to be stored and to effect readout; circuit means coupled to said input terminal for applying said electrical impulses to said device so that each impulse transfers a glow discharge to the next higher digit representing cathode; a second group of digit representing and glow transfer cathodes alternately arranged in a closed glow transfer path to effect glow transfer in one chosen direction along said path, said direction being opposite to that of the glow transfer effected by said first group of cathodes; glow transfer means between each cathode of each group and between each digit representing cathode of one group and a cathode of the other group, the latter cathode representing the digit which is the nines complement of the digit represented by the former cathode; and means for rendering said device operable.

2. The accumulating device set forth in claim 1 including a voltage source; voltage switching means connectable to said voltage source and to said digit representing cathodes, one group at the time, a connection to said first group of cathodes providing for storage of said electrical impulses and a connection to said second group of cathodes providing for readout of digit representing impulses stored in complement form; said circuit means including a common connection between all said transfer cathodes and said input terminal for applying said impulses simultaneously to all said transfer cathodes.

3. In a gaseous discharge device of the glow transfer type; a first group of electrodes arranged along a first pre-selected path to sequentially transfer a glow discharge therealong in one direction in response to each data representing electrical impulse stored; an input terminal adapted to receive said impulses; circuit means connecting said input terminal and said first group of electrodes; a second group of electrodes arranged along a second pre-selected path to sequentially transfer a glow discharge therealong in a direction opposite to the direction of the glow transfer along the said first preselected path; glow transfer means between said first group of electrodes and said second group of electrodes; an anode common to each said group of electrodes; and means for rendering said device operable.

4. The device set forth in claim 3 wherein each of said group of electrodes comprises a predetermined number of cathodes, successive ones of which are alternately glow transfer and glow position cathodes, each cathode having a reentrant portion to accommodate a glow discharge between that cathode and the anode; each position cathode of said first group is connected to one position cathode of said second group by said glow transfer means; and selectively energizable means connectable to each group of cathodes for changing the relative voltages thereon to effect a glow transfer from a cathode of one of said group to the cathode of the other group.

5. The device as set forth in claim 4 wherein said glow transfer means include a wire affixed at one end of the cathode to which the glow discharge is transferred and having its other end extending freely intermediate the reentrant portion of the cathode from which the glow is transferred and the anode.

6. In a gaseous discharge tube of the glow transfer type wherein a glow discharge is transferred from one position of stable glow discharge to the next such position in response to each digit stored including an anode; a first section for effecting storage, said section including a plurality of cathodes arranged in a first closed glow transfer path, ionic insulating means separating each cathode from adjacent cathodes to isolate the ionization resulting from a glow discharge to any cathode

from the other cathodes, a glow transfer wire for each cathode and having one end attached thereto and its other end extending into a region of intense ionization of an adjacent cathode to transfer a glow discharge from the latter cathode to the former in response to a preselected voltage change; a second section for effecting readout of digital values stored in said first section, said second section including a plurality of cathodes arranged in a second closed glow transfer path, ionic insulating means separating each cathode from adjacent cathodes to isolate the ionization resulting from a glow discharge to any cathode from the other cathodes, a glow transfer wire for each cathode and having one end attached thereto and its other end extending into a region of intense ionization associated with an adjacent cathode to transfer a glow discharge from the latter cathode to the former in response to a preselected voltage change, said wires being arranged so that the glow transfer along said second path is always opposite to that along said first path.

20 7. The gaseous discharge tube set forth in claim 6 wherein said cathodes arranged in said first path comprise digit position cathodes with a storage transfer cathode intermediate each two successive digit position cathodes; said cathodes arranged in said second path 25 comprise a number of complement position cathodes equal to the number of said digit position cathodes and having a complement glow transfer cathode intermediate each two successive complement position cathodes; a glow transfer wire is connected at one end to each 30 digit position cathode and has its other end extending into a region of intense ionization associated with one complement position cathode and a glow transfer wire is connected at one end to each complement position cathode and has its other end extending into a region 35 of intense ionization associated with one digit position cathode, thereby providing for transfer of a glow discharge from any digit position cathode to one complement position cathode and vice versa.

8. A gaseous discharge tube set forth in claim 7 40 wherein said cathodes comprise ten digit position cathodes, ten storage glow transfer cathodes, ten complement position cathodes, and ten complement glow transfer cathodes; and connections are provided to apply input pulses to be stored simultaneously to all storage glow transfer and complement glow transfer cathodes.

9. The gaseous discharge tube set forth in claim 9 45 wherein eight of said digit position cathodes are commonly connectable to a source of supply voltage and the remaining two digit position cathodes are separately connected to the source of supply voltage, an output terminal connected to one of said remaining two cathodes to provide an output pulse to indicate the digital value stored in the tube, and a terminal connected to the other of said remaining two digit position cathodes to provide a carry manifestation to indicate that a cycle of tube operation is completed; nine of said complement position cathodes are commonly connectable to the source of supply voltage and the remaining cathode is separately connectable to the source of supply voltage and provided 50 with an output terminal to indicate the digital value stored in complement form; and voltage switching means connected to switch said supply voltage from said digit position cathodes to said complement position cathodes to transfer a glow discharge from the former to the latter and from said complement position cathodes to said digit position cathodes to transfer a glow discharge from the latter to the former.

10. In a gaseous discharge storage tube, a first group 55 of electrodes for effecting storage, circuit means connected to energize said electrodes so that each pulse applied thereto stores one manifestation in the tube, a second group of electrodes for effecting readout of a value stored in complement form in said first group of electrodes, a switching means synchronized with said cir-

cuit means for applying electrical changes to said second group of electrodes for effecting read out.
